LOUDSPEAKER CABINET

Dallas Richard Wilder, 1253 W. Diversey Parkway,
Chicago, Ill. 60614

Filed May 2, 1966, Ser. No. 2,096

Term of patent 14 years

(Cl. D26—14)

FIGURE 1 is a perspective view of a loudspeaker cabinet, showing my new design;

FIG. 2 is a front elevational view of the design;

FIG. 3 is a side elevation thereof; and

FIG. 4 is a perspective view of a modified embodiment of the loudspeaker cabinet shown in FIG. 1.

The dominant features of my design reside in the portions shown in full lines. The loudspeaker cabinet is further characterized by the specific configuration of the front panel as best illustrated in FIGS. 1, 2 and 4.

I claim:

The ornamental design for a loudspeaker cabinet, substantially as shown and described.
